INVENTOR

Joseph Wade

UNITED STATES PATENT OFFICE.

JOSIAH WADE, OF HALIFAX, COUNTY OF YORK, ENGLAND.

BORING-TOOL.

SPECIFICATION forming part of Letters Patent No. 280,420, dated July 3, 1883.

Application filed May 2, 1883. (No model.) Patented in England March 30, 1883, No. 1,603.

To all whom it may concern:

Be it known that I, JOSIAH WADE, a citizen of Great Britain, residing at Halifax, in the county of York, England, have invented certain Improvements in Cutters for Boring-Machines, of which the following is a specification.

My invention relates to improvements in boring-bars; and the invention consists in providing the bar with two cutters arranged in a cross slot or aperture in the bar, so as to project beyond its periphery, and with means for uniformly regulating the projection of said cutters beyond the bar, so that holes of different diameters may be bored at will, and for clamping the cutters fast, all as will be hereinafter more fully set forth.

In the drawings which serve to illustrate my invention, Figure 1 is a side view of a boring-bar provided with my improvements. Fig. 2 is a longitudinal vertical mid-section of same. Fig. 3 is a cross-section on line 3 3 in Fig. 1. Fig. 3^a shows the adjusting or setting screw detached, and Fig. 4 is a cross-section on line 4 4 in Fig. 1. Figs. 5, 6, 7, 8, and 9 illustrate modifications which will be referred to hereinafter.

Referring to the first four figures, A represents the boring-bar, provided with a fixed collar, B, a male screw, C, and a diametrical cross slot or mortise to receive the cutters D, E. These cutters may be made from tool-steel in any way; but I prefer to make them in one piece, then drill a hole through the center, ream it out to a conical form, and then cut the piece in two by a cross-cut through the center of said hole. The reason for this will be made clear hereinafter.

G is a loose collar, which slips over the bar, and H is a nut. By screwing up this nut the collar G is forced against the cutters, and they in turn against the fixed collar B, whereby the cutters are firmly clamped and held. To further steady their lateral edges, however, I recess the inner faces of the collars B and G, to receive said edges of the cutters, as clearly shown, especially in Fig. 1.

I is a setting or adjusting screw, which has a conical portion, e, (see Fig. 3^a) that engages the conical hole before referred to, one-half of which is in each of the juxtaposed butts of the cutters D, E. By screwing in the screw I the cutters will be driven outward, as will be

clearly understood, by the action of the coned portion e of the screw, which performs the functions of a wedge. When properly set or adjusted, the cutters are firmly fixed by screwing up the nut H.

Figs. 5 and 6 illustrate the application of my invention to ordinary boring-bars, Fig. 6 being a sectional view, and Fig. 5 a plan. In this construction the collar B and male screw C are formed on a sleeve, J, which slips snugly over the bar, and is held in place by means of keys or pins M, or some other equivalent device. The bar must have a cross-slot to receive the cutters, and a hole to receive the screw I. The sleeve J only is shown in section in Fig. 6.

Figs. 7 and 8 illustrate a modification in which two projecting parts, a and b, on the cutters D and E, respectively, take over the loose collar G, and the latter is provided with two like cams, c and d, which, when said collar is turned, take under the projections a and b and drive out the cutters. This device is an equivalent of the screw I. By loosening nut H the collar G may be turned until the cutters are properly protruded, when it can be clamped fast by the nut.

Fig. 9 is a sectional view illustrating another modification, in which a conical nut, K, is made to displace the fixed collar B. This nut takes under beveled projections a b on the cutters and drives them outward. The nut K is designed to take the place of the screw I and the cams c d.

I am aware that it is not new in reamers and metal-boring tools to arrange the cutters so that they may be adjusted radially for boring holes of greater or less diameter, and I am also aware that conical screws have been employed for expanding the same. Therefore I make no claim to these features.

Having thus described my invention, I claim—

1. The combination, with the boring-bar provided with a slot or mortise to receive the cutters, a fixed collar, B, having a recess in its face to receive the lateral edges of the cutters, a loose collar, G, recessed similar to collar B, and a nut, H, and male screw C, of the cutters D and E, and means, substantially as described, for driving the cutters outward uniformly, substantially as set forth.

2. The combination, with the boring-bar provided with a slot or mortise to receive the cutters, a fixed collar, B, having a recess in its face to receive the lateral edges of the cutters, 5 a loose collar, G, recessed similar to collar B, and a nut, H, and male screw C, of the cutters D and E, and the screw I, provided with a coned part, e, all arranged to operate substantially as set forth.

In witness whereof I have hereunto signed to my name in the presence of two subscribing witnesses.

JOSIAH WADE.
